UNITED STATES PATENT OFFICE.

WILBUR S. CLARK AND JOHN A. PENN, OF CAMDEN, NEW JERSEY.

RESERVE-FUEL-FEEDING DEVICE.

Application filed March 24, 1922. Serial No. 546,273.

To all whom it may concern:

Be it known that we, WILBUR S. CLARK and JOHN A. PENN, citizens of the United States, residing at Camden, county of Camden, and State of New Jersey, have invented certain new and useful Improvements in Reserve-Fuel-Feeding Devices, of which the following is a specification.

This invention has reference to reserve gasoline supply devices or valves operative for use in connection with the gasoline supply tank of an automobile which when the gasoline reaches a predetermined low level, will cease to feed gasoline to the engine, but which when manipulated will feed a reserve supply to the engine so that after the driver has been warned that the gasoline supply in the tank is getting low, he will have sufficient gasoline to take him to the next supply station for refilling of the tank.

In addition to the above general statement of object of our invention, it is a further object to improve the construction of devices of this class and particularly that shown and described in our prior application filed August 23, 1921, Serial No. 494,656, in which there is provided a tube for controlling the supply or discharge of the gasoline from the tank to the carburetor of the engine; the improvements consisting in providing a structure which will obviate the necessity of employing spaced upper and lower holes or ports so that the lower port for the discharge of the reserve supply may be eliminated; to provide an improved and simple arrangement in connection with the sediment bulb and valve associated with the outlet of the tank for co-operation with said tube whereby the discharge of the reserve supply can be easily, positively, and effectively controlled; and further, to provide improved means facilitating the application of said tube to the tank so as to obviate the necessity of inserting the same at the bottom or outlet with considerable difficulty and to associate with said tube, simple and novel means for lowering the same or raising and locking it in an elevated position when the reserve supply of the gasoline is being consumed.

A still further object of the invention is to generally improve, simplify and enhance the structure and facilitate the manufacture of devices of the character to which the invention relates.

These objects, and other advantageous

ends which will be described hereinafter, we attain in the following manner, reference being had to the accompanying drawings in which—

Figure 1 is a fragmentary sectional elevation taken longitudinally through a gasoline supply tank and illustrating the application of the improved reserve gasoline supply device thereto in elevation; the same being illustrated with the major portion of the gasoline having been exhausted and when necessary to draw on the reserve supply,

Figure 2 is a vertical sectional elevation in a plane at right angles to Figure 1 and taken on the line 2—2 of Figure 1, the parts being in the same position as in Figure 1,

Figure 3 is a view similar to Figure 2, but showing the tube raised and in position to discharge or feed the reserve quantity of gasoline to the motor,

Figure 4 is a fragmentary perspective view showing the manner of applying the tube to the gasoline supply tank, in connection with its guiding and supporting means; the parts being in the position when initially applied,

Figure 5 is a view similar to Figure 4, but showing the parts after being partially rotated,

Figure 6 is a detail sectional view showing a locking device or latch employed for raising the tube and holding the same in an elevated position, and

Figure 7 is a perspective view of the latch.

Referring to the drawings in detail, in which for purposes of illustration is shown the preferred embodiment of the invention, and in which like reference characters designate corresponding parts throughout the several views, 10 represents a gasoline supply tank such as employed on automobiles and 11 a sediment bulb, both of which are of well known construction. The bottom 12 of the tank is provided with an outlet nipple or collar 13, the bore or hole of which is internally threaded as indicated at 14 in which the stem 15 of the sediment bulb 11 is threaded, the collar being suitably tapped to receive the externally threaded reduced stem portion of the bulb. The stem 15 has a cavity or counter-bore 16 leading downwardly from its top and communicating with the space within the bulb 11, said space being contracted as shown at 17 to a diam-

2

eter less than that of the cavity 16, the portion 17 of normal diameter resulting in the formation of a shoulder 18 at the bottom of the cavity and facing upwardly. The 5 bulb has means of connection with a pipe extending to the carburetor for supplying gasoline to the motor, such connection being represented at 19 and preferably detachable from the sediment bulb and valve 10 of which it forms a part and which facilitates the cleaning thereof, in connection with a drain or pet cock for the connection of which facility is provided at the bottom of the bulb, as indicated at 20.

15 A valve 21 at the lower end of the contracted portion or bore 17 of the sediment bulb and valve, and preferably in the form of a turn-plug provided with a controlling handle 22, is provided for permitting the 20 feed of the gasoline or cutting off the same as desired. In the normal and ordinary use of the tank and bulb, the valve 21 is opened and the gasoline from the tank passes downwardly through the cavity and 25 then into the space or chamber at the interior of the bulb 11 and outwardly through the pipe connection 19 to the carburetor for furnishing a proper supply to the engine. Any sediment collected in the lower portion 30 of the bulb can be removed by opening the usual cock positioned at the bottom of the bulb through the medium of the connection 20 heretofore referred to.

35 In applying our invention to the structure above described, and particularly with a sediment bulb and valve having the counter-bore or cavity 16 enlarged with respect to the normal bore portion 17 as described, the top wall 23 of the gasoline supply tank 10 40 is provided immediately above the outlet opening and nipple 13, preferably in vertical alignment therewith, a hole 24 adapted to receive a tube 25 which snugly and slidably fits the bore portion 17 at the stem of the bulb, but which is of reduced diameter with respect to the cavity 16 so as to form 45 an annular channel in the space around the lower end of the tube and between the periphery of the tube and the enlarged wall 50 of the cavity as clearly shown in Figures 2 and 3 of the drawings. This is true at all times, whether the tube is engaged in the bore 17 or elevated with its lower extremity above the shoulder 18 at the upper end of 55 said bore portion, the tube fitting said contracted bore portion as shown in Figure 2, in such a manner as to normally cut off the reserve supply of gasoline from within the tank so that the same will not be discharged from the tank 10 when the valve 60 21 is open, although the bore of the tube will be aligned with the passage of the valve. It will be noted that the hole 24 in the top of the tank is sufficiently large to allow the 65 lower portion or flange 26 of a small exter-

nally threaded sleeve or bushing 27 which is snugly mounted for sliding movement on the tube 25, to pass therethrough. In order to secure the threaded sleeve in position as a guide for the tube in the raising and 70 lowering of the latter, and prevent its displacement upwardly through the hole or opening 24, in the top of the tank, a split spring washer 28 is mounted upon the sleeve, being threaded or turned helically thereon 75 and the split 29 so spacing the ends of the washer that sufficient distance will be allowed to admit the thickness of the top wall of the tank so that by turning the split washer, it will pass through the hole in 80 the tank when applied in the manner shown in Figure 4 of the drawings and rotated as shown in Figure 5 so as to engage the bottom surface of said wall as clearly shown in Figures 1, 2 and 3. Since this washer is of greater diameter than said hole, it 85 will serve to prevent the lower enlarged portion or flange of the threaded sleeve, formed as a head on one end thereof, from passing upwardly through the hole when a 90 nut 30 is screwed down on the same to engage the outer surface of the top wall 23 of the tank 10 or a packing washer 31 suitably interposed between the nut and said wall. It is also to be understood that any 95 other suitable securing means may be employed for fastening the sleeve in position, the essential feature being that the sleeve forms a guide to snugly receive the tube so that a relatively long bearing is produced 100 serving to guide or direct the lower end of the tube into the restricted or normal bore portion 17 at the stem of the bulb and also to serve by reason of said frictional engagement to adjust or hold the tube in any desired position of elevation.

105 In lieu of providing the tube 25 with upper and lower spaced holes as is usual, and as shown and described in our pending application above referred to, so as to admit and control the flow of the gasoline above and below the reserve level from the tank, in the present instance, the lower hole of the tube is omitted, the lower end of the tube being freely open; however, as in the previous construction and openings 32 being provided in diametrically opposed positions in the wall of the tube to form ports considerably spaced from the lower end of the tube and corresponding to the 115 reserve level of the gasoline or other fluid in the tank as controlled by the device, after the major quantity of gasoline has been consumed and discharged through said ports produced by the holes 32, downwardly 120 through the tube, valve 21 and outlet 19 to the carburetor for the operation of the motor. In this position the tube is lowered so as to engage the restricted bore portion 17 and in order to limit the downward move- 125 130

ment of the sleeve and the upward movement or elevation of the tube, as well as to lock the tube in an adjusted or elevated position, the following construction is provided.

5 At a point spaced from the upper end of the tube near the top wall 23, a stop member or shoulder 33 is provided, the tube being flattened as indicated for the purpose of enlarging the same whereby the sleeve 27, 10 should it drop on the tube, will engage said enlargement produced by the flattened or pressed portion resulting from opposite indentations in the tube and thus prevent the sleeve from dropping below a predetermined 15 point so that when the tube is being applied and fastened in position at the top wall of the tank through the medium of the hole 24, sleeve 27, washer 28 and fastening means described, said sleeve may be held 20 firmly in contact with the inner surface of said top wall around the hole 24 through the medium of said washer, as well as permitting the tube to be applied at the top in lieu of necessitating its application in an inconvenient and undesirable manner at the bottom of the tank.

In addition to limiting the downward movement of the threaded sleeve in applying the tube to the tank for service, the enlargement forming the stop member 33 limits the upward movement of the tube from the position shown in Figures 1 and 2 of the drawings to the position shown in Figure 3 of the drawings by engagement with the sleeve at 35 its bottom flange 26, at which time the lower or outlet end of the tube will be withdrawn from the restricted bore portion 17 to a point above the shoulder 18 whereby the reserve supply of gasoline below the level of the 40 ports or holes 32 as shown in Figures 1 and 2 of the drawings may be discharged through the cavity or annular space between the tube and the wall of said cavity directly from the tank and without passing through the tube, as clearly shown in Figure 3 of the drawings. In this manner the intervention of the tube in the discharge of the reserve supply of gasoline from the tank is unnecessary and this also facilitates the complete 45 discharge of the tank should it be desired to drain and clean the same since the outlet around the tube is entirely open and wholly below the inner surface of the bottom of the tank.

50 In order to raise the tube so as to elevate the lower end thereof from the position shown in Figure 2 and in which position the major quantity of the gasoline will be fed to the motor when the supply tank is filled, until the level reaches the holes 32, to the 55 position shown in Figure 3 of the drawing for feeding the reserve supply to the motor, a suitable locking means is provided at the upper end of the tube and co-operates with the top of the tank or nut 30 which serves

as a securing means for the sleeve 27. For this purpose a nut or cap 34, which may be in the form of a cap nut, is threaded or otherwise mounted at the upper end of the tube so as to close said end and pivotally 70 receive an angular bail or latch 35. For this purpose, the bail or latch is preferably made of wire and bent upon itself intermediately of its ends so that the extremities 36 thereof are extended in opposite directions sprung 75 into a transverse opening in the cap. The sides are bent at right angles to the portions 36 and substantially parallel to each other toward the intermediate or bight portion 37. The sides, that is the latch or bail as a whole, 80 has its free end portion bent substantially at right angles as indicated at 38 so that when the latch is swung upwardly, the finger may be inserted beneath the hook formed by the angularly directed bight portion, 85 where it may be grasped or engaged with any suitable instrument for exerting upward pull thereon and thereby change the position of the tube from that shown in Figures 1 and 2 to that shown in Figure 3, after which the 90 latch may be swung downwardly as shown in Figure 3 to frictionally engage the tube at its opposite sides and also the nut 30 so as to lock the tube in a raised position when feeding the reserve supply of the gasoline. 95

In this manner, when the reserve level has been reached, the motor will stop, thus warning the driver that the supply is getting low, but the reserve supply will permit further travel until such time as the 100 supply in the tank may be replenished. In addition to the latch serving to hold the tube in an elevated position, the frictional engagement of the tube with the bore of the sleeve 27 will ordinarily suffice but the 105 latch will positively insure against dropping of the tube and once it has been raised and locked for the feeding of the reserve supply of gasoline, the driver need not be concerned with such feeding but should 110 drive to the nearest gasoline supply station to replenish the tank with gasoline. It should also be noted that the means for mounting the tube in position for sliding movement as described in order to control 115 the feed of the gasoline, permits the tube to be placed in position conveniently from the hole 24 in the top of the tank, instead of necessitating that it be applied at the bottom as in our prior construction. The 120 present construction is also more simple and practical as well as more durable in use and the supporting means for the tube will especially remain operative for a somewhat indefinite period. The application of the sediment bulb and valve and also the application of the tube in its interfitting engagement therewith, may be more readily accomplished. The lower end of the tube 125 is flangeless, obviating the use of intricate 130

parts in the cavity at the stem of the sediment bulb which are likely to get out of working order and by reason of the fact that the tube directly co-operates with the restricted or normal bore portion of the bulb, it is only necessary to provide the upper series of holes or ports for the discharge of the gasoline.

While we have described our invention as taking a particular form, it will be understood that the various parts of our invention may be changed without departing from the spirit thereof, and hence we do not limit ourselves to the precise construction set forth, but consider that we are at liberty to make such changes and alterations as fairly come within the scope of the appended claims.

Having thus described our invention, what we claim as new and desire to secure by Letters Patent is:—

1. The combination with a gasoline supply tank having an outlet and a sediment bulb secured in said outlet and provided with a valve for controlling the discharge of the gasoline to the motor and a counter-bore in the stem thereof; a tube of less diameter than said counter-bore and snugly fitting the bore portion therebelow, the lower end of the tube being open and said tube having a perforation spaced from its lower end and the remaining portion of its wall imperforate whereby the major quantity of gasoline will be discharged through said perforation and tube when the tube is engaged in the lower bore portion until a reserve level is reached below said opening and to discharge said reserve supply when the lower portion of the tube is moved into said counter-bore, said tube being slideable through the top of the tank and having an indentation serving as a stop to limit its upward movement; and a pivoted latch carried by the upper end of the tube and arranged to hold the same in said raised position; substantially as described.

2. In combination with a tank in the class described, having an opening in the top, said tank having an outlet and a tube co-operating with said outlet; guiding means for said tube at said opening and including a split washer adapted to accommodate the thickness of the tank wall at the opening and to enter beneath the same upon turning the washer; a sleeve snugly mounted on the tube; means to limit the downward movement of the sleeve on the tube, said sleeve supporting the washer for contact with the inner surface of said top wall; and securing means on the sleeve externally of said wall to draw the washer against said inner surface; substantially as described.

3. In combination with a tank in the class described, having an opening in the top,

said tank having an outlet and a tube co-operating with said outlet; guiding means for said tube in said opening and including a split washer adapted to accommodate the thickness of the tank wall at the opening to enter beneath the same upon turning the washer; a sleeve snugly mounted on the tube; means to limit the downward movement of the sleeve on the tube, said sleeve having a bottom flange upon which the washer rests, the sleeve extending upwardly through the hole around the tube; a washer on the sleeve and engaged with the top surface of said wall; a securing nut on the sleeve to secure said parts to said wall; and a latch pivoted to the upper end of the tube and adapted to swing into engagement with the nut to keep the tube in a raised position; substantially as described.

4. In combination with a supply tank having an opening therein; a tube frictionally and slidably mounted in said opening; a cap on the tube; and a latch pivoted in the cap, said latch having an angular portion forming a hook for raising the tube when the latch is swung upwardly, and adapted when swung downwardly to brace and hold the tube in a raised position; substantially as described.

5. A device of the character described for use in connection with means including a liquid supply tank and an outlet passage for the liquid from the tank, said device including a conduit tube having a flangeless portion movable within the passage, the lower end of the tube being freely open, said portion being imperforate and said tube having ports uniformly spaced from the lower end thereof and said ports being always positioned in the tank, said outlet having a restricted bore portion and a cavity enlarged relative thereto to provide an annular channel around the tube; means for inserting and slidably supporting the tube at the top of the tank and frictionally engaging the same to hold the tube in a raised position with the lower end thereof above the restricted bore portion whereby the outlet is open through said channel directly from the tank; means for limiting the upward movement of the tube; and means for raising the tube, said latter means serving to lock the tube in a raised position; substantially as described.

6. A device of the character described for use in connection with means including a liquid supply tank and an outlet passage for the liquid from the tank, said device including a conduit tube having a flangeless portion movable within the passage, the lower end of the tube being freely open, said portion being imperforate and said tube having ports uniformly spaced from the lower end thereof and said ports being always positioned in the tank, said outlet having a restricted bore portion and a cavity enlarged

relative thereto to provide an annular channel around the tube; means for inserting and slidably supporting the tube at the top of the tank and frictionally engaging the same 5 to hold the tube in a raised position with the lower end thereof above the restricted bore portion whereby the outlet is open through said channel directly from the tank, said tube being formed to engage its mounting to limit the raising of the tube and serving also to limit the downward displacement of said mounting on the tube, the tube being held in position by frictional engagement with its mounting; and a locking bail pivotally mounted on the upper end of the 10 tube and serving as a hook to raise the tube when the bail is swung upwardly, said bail being designed to swing downwardly in engagement with the mounting and to straddle the tube so as to hold the tube in a raised 20 position projecting above the tank; substantially as described.

In testimony whereof we have signed our names to this specification in the presence of two subscribing witnesses.
